UNITED STATES PATENT OFFICE.

HAROLD A. SWAN, OF CORONADO, CALIFORNIA.

ABRADING AND POLISHING TOOL.

Application filed November 23, 1925. Serial No. 71,006.

This invention relates to certain new and useful improvements in abrading or polishing tools, and has more particular reference to tools of the above kind of relatively small size and light construction adapted to be readily carried in the hand and manually pushed over the surface to be abraded or polished.

The primary object of the invention is to provide an abrading or polishing tool of the above kind embodying a single abrading or polishing drum as well as embracing a construction which is simple and durable in form and effective in operation.

A further object of the invention is to provide simple and effective means for raising and lowering the abrading or polishing drum whereby the latter may be brought to bear upon the surface to be abraded or polished with the required pressure or disengaged from such surface, as desired.

Still another object of the invention is to embody a motor for driving the abrading or polishing drum in the tool structure so that a compact construction is had, and to provide a gearing for operatively connecting the motor to the drum, which gearing is in the nature of a reduction gearing for permitting the use of a relatively small motor capable of being housed within the drum and having an armature adapted to rotate at a relatively high speed for insuring sufficient power to cause rotation of the drum at a relatively lower speed even though resistance to rotation of the drum is experienced by reason of engagement of the drum with the surface to be abraded or polished.

A still further object of the invention is to make thoroughly practical provision for mounting of the motor within the abrading or polishing drum and for operatively connecting the armature shaft of the motor with the drum.

A still further object of the invention is to provide a tool of the above kind embodying a casing for enclosing the major portion of the polishing or abrading drum, and wherein said casing is constructed with a cover section adapted for removal or to be opened whereby the abrading or polishing drum together with its enclosed motor and gearing may be removed from the casing, as a unit, for renewal or repair purposes.

Other objects will appear as the nature of the invention is better understood, and the same consists in the novel form, combination and arrangement of parts hereinafter more fully described, shown in the accompanying drawing and claimed.

In the drawings, where in like reference characters indicate corresponding parts throughout the several views—

Figure 1 is a side elevational view of an abrading or polishing tool constructed in accordance with the present invention;

Figure 2 is a vertical longitudinal sectional view thereof;

Figure 3 is a horizontal longitudinal sectional view of the same;

Figure 4 is a transverse sectional view of the device shown in Figure 1; and

Figure 5 is an enlarged edge elevational view of one of the eccentric rings forming part of the means for raising and lowering the polishing drum.

Referring more in detail to the drawings, the present invention embodies a stock plate 5 provided with a flat under surface adapted to flatly engage the surface to be abraded or polished, and this stock plate is provided near its forward end with a relatively wide transverse slot 6, the ends of which are extended upwardly a slight distance in the side or longitudinal flanges 7 rigidly provided on the plate 5 as shown. The flanges 7 are connected by a pair of transverse arcuate walls or webs 8 which are arranged at the front and rear sides of the slot 6 and cooperate with the portions of the flanges 7 therebetween to form the lower section of a casing so that said lower section is rigid with the stock plate 5. The casing is of cylindrical form and embodies a separate upper or cover section 9 which may be removable, but which is preferably hinged at its forward side as at 10 to the upper edge portion of the forward arcuate wall 8. The upper or cover section 9 of the casing is thus capable of being swung upwardly and forwardly to open position for a purpose which will later become apparent, and rigidly formed upon the upper edge portion of the rear curved wall 8 and the rear edge of the cover section 9 are cooperating lugs 11 and 12 with which are associated means for retaining the cover section 9 closed. This means may embody bolts 13

hinged to the lugs 11 of the rear wall 8 and adapted to be swung into or out of slots provided in the lugs 12 carried by the cover section 9, suitable wing nuts 13 being threaded upon the free ends of the bolts 13 and adapted to bear against the upper surfaces of the lugs 12 for retaining the cover section 9 tightly closed. Obviously, by loosening the wing nuts 14, the bolts 13 may be swung rearwardly and downwardly out of the slots of the lugs 12 so that the cover section 9 is released and may then be swung upwardly and forwardly to open position. The above construction provides a horizontal transverse cylindrical 15 casing having flat circular side or end walls, and these side or end walls are formed with central relatively large circular openings in which rotatable cam rings 15 are journaled. The casing is formed with outwardly projecting annular flanges 16 about these openings, which flanges are internally rabbeted at their outer ends, and formed upon the outer ends of the eccentric rings 15 are external annular flanges 17 adapted to fit in 20 the grooves or rabbets of the flanges 16 for limiting inward movement of the eccentric rings 15 relative to the casing or preventing accidental displacement of such eccentric rings inwardly through the openings of the 25 casing as will be apparent from Figures 3 and 4.

Disposed within the casing is an electric motor 18 of the well known conventional type embodying a rotatable armature fixed to an 30 armature shaft 19 and surrounded by a stationary field carried by a casing 20 in which the armature shaft 19 is journaled by the use of suitable bearings as indicated at 21. The eccentric rings 15 are rotatably fitted on 35 supporting disks 22, one of which is provided with perforations as at 23 for a purpose which will later become apparent, and which is rigidly attached to the frame 20 of the motor by suitable means such as screws 24 40 which pass through openings in this disk 22 and are threaded into sockets of the motor casing 20 as shown more clearly in Figure 3.

The motor 18 is centrally disposed within 45 an abrading or polishing roller 25 which is also concentric with and disposed within the casing of the stock plate 5, and this abrading or polishing drum has an end wall 26 formed with a central opening into which a cylindrical portion of the motor casing 20 projects, a suitable anti-friction bearing 27 being interposed between this wall 26 and the casing 20 for permitting the drum to freely rotate 50 relative to the motor at this point. The abrading or polishing drum further includes another end or side wall 28 which has a central opening of such large size that the wall 28 is substantially in the nature of ring. A spider or disk 29 is fitted in the opening of 55 the wall 28 and is rigidly attached to the

other supporting disk 22 by means of screws 30 or the like. An anti-friction bearing 31 is provided between the spider or disk 29 and the end wall 28 so that the drum is supported at this end for free rotation relative 60 to the spider or disk 29, and the armature shaft 19 projects into a socket in the center of the spider or disk 29 as indicated at 32. An anti-friction bearing 33 is provided between the spider or disk 29 and the free end 75 of the armature shaft 19 so that the armature shaft may freely rotate without tending to cause rotation of the spider or disk 29.

Secured upon the projecting end portion of the armature shaft 19 is a spur pinion 34 80 which meshes with a pair of relatively large spur gears 35 that are journaled upon suitable stub shafts which are carried by and project laterally inwardly from the spider or disk 29 at opposite sides of the pinion 34. The gears 85 35 mesh with an internal ring gear 36 which surrounds said gears 35 and is secured in a suitable manner to and within the adjacent end of the drum 25. It is thus apparent that when the motor 18 is placed into operation 90 so as to cause rotation of the armature shaft 19, the rotation of said armature shaft is transmitted to the drum 25 through the gearing described, and the motor is effectively supported so that the drum may freely rotate 95 about the same.

The eccentric rings 15 may be provided with pairs of diametrically opposed studs or pins 37 which project outwardly, and disposed to straddle the casing is a bail or U-shaped lever 38, the ends of which are provided with pairs of openings adapted for detachable reception of the studs or pins 37. The bail or lever 38 is preferably constructed of resilient sheet metal so that the legs thereof 100 may be spread apart for disengaging from the studs or pins 37 whereby removal of the lever or bail 38 is permitted for allowing the upper casing section 9 to be opened. By swinging the lever 38 the eccentric rings 15 105 may be rotated about the disks 22 and relative to the casing so as to effect raising or lowering of the drum 25 and parts carried thereby, depending upon the direction in which the lever 38 is swung. It is thus apparent that the 110 surface of the abrading or polishing drum may be brought into or out of contact with the surface to be abraded or polished upon which the plate 5 rests and that the pressure 115 with which the drum 25 engages said surface may be regulated. Any suitable means may be provided to hold the lever 38 in adjusted position such as an inwardly projecting lug on the intermediate portion of the lever 38 120 adapted to engage in notches 39 provided in the outer surface of the cover section 9. The lever 38 may also be provided with any suitable form of handle for facilitating swinging of the same if found necessary or desirable.

A conduit or rigid pipe 40 is horizontally 130

disposed at one side of the casing with its forward end projecting through and fitted in an opening of the adjacent flange 16 and extending through a circumferentially elongated 5 slot 41 in the adjacent eccentric ring 15 (see Figure 5), whereby rotation of said eccentric ring is permitted. The forward end of the conduit 40 is threaded into an opening in the adjacent apertured disk 22, and it is thus ap- 10 parent that the disk 22 having the apertures 23 is restrained from rotation relative to the casing by means of the conduit 40 so that tendency of the motor casing and the spider 29 to rotate is overcome. The conduit 40 pro- 15 jects rearwardly to the rear side of the casing of the plate 5 where it has a suitable electric switch 42 fixed thereto which leads a suitable attachment cord 43 whose free end may be equipped with an attachment plug for fa- 20 cilitating connection of the tool motor with a suitable source of electricity such as an attachment plug socket of a house wiring system. The current is supplied from the switch 42 to the motor 18 by means of a cable which 25 passes through the conduit 40 and then through one of the apertures 23 of the adjacent disk 22, into the motor casing 20 as shown in Figure 3. The switch 42 is thus mounted in convenient position to render the motor 18 op- 30 erative or inoperative at will. The opening in the flange 16 through which the conduit 40 passes is closed by the adjacent lower edge of the adjacent side wall of the cover section 9 so that when said cover section 9 is opened, the 35 conduit 40 may be removed with the eccentric rings, disk 22 and the motor carrying abrad- ing or polishing roller 25 from the lower rigid section of the tool casing.

A suitable diaphragm 44 may be suitably 40 mounted within the drum 25 adjacent to and at the inner side of the gears 35 and pinions 34 for retaining oil in the several adjacent bearings, and act as an oil guard for the adjacent surface of the motor. Suitably fixed upon the 45 rear portion of the stock plates 5 at the rear side of the casing of the latter is a handle 45 for facilitating pushing of the tool over the surface to be abraded or polished. The handle 45 is disposed centrally between the 50 flanges 7, and in order to facilitate forcible engagement of the plate 5 and the drum 25 with the surface to be abraded or polished with the required pressure, a further bail handle 46 may be fixed to the rigid lower sec- 55 tion of the drum casing with its ends secured to the sides of the latter as shown clearly in Figure 1. The eccentric rings 15 may be pro- 60 vided at their inner ends with internal annular flanges as at 47 against which the inner ends of the disks 22 are positioned and se- 65 cured by the screws 24 and 30, whereby acci- dental outward displacement of the eccentric rings is prevented.

From the foregoing description it will be seen that the present invention eliminates the

necessity for external gearing to drive the drum and the reduction gearing between the motor and the drum enables driving of the drum with sufficient power and at a relatively low speed by the use of a relatively small high speed motor which is compactly arranged relative to the drum for economizing space and making the entire tool construction quite compact. 70

In operation the switch 42 is turned on for 75 causing the motor 18 to operate, whereupon the drum 25 is rotated through the gearing described. The tool is then placed upon the surface to be abraded or polished and manually pushed thereon as is obvious to those skilled in the art. 80

The abrading or polishing drum preferably consists of a cylinder onto which are fitted concentric bands 48 and 49, the band 48 being of rubber or other suitable material and the band 49 being of sand paper or other abrading or polishing material depending upon the work to be done. The band 48 is preferably of rubber for furnishing a yielding padding between the polishing or abrad- 90 ing band 49 and the drum proper and at the same time preventing slipping of the band 49 circumferentially of the drum proper. 95

The ring gear 36 and drum wall 28 are provided with transverse alined openings as 95 at 48^b which are arranged in a circular series, and fixed to the inner side of the ring gear 36 at the inner ends of such openings are dished fan blades 49^b. Thus, when the drum 25 is rotated the blades 49 are carried around 100 so as to draw air into the drum through the openings 23 of the left hand disk 22 and then force the air out of the drum through the openings 48^b into the drum casing. This keeps the motor and bearings cool, and the 105 air is discharged from the drum casing through the slot 6 so as to blow loose particles from the surface being abraded or polished for keeping the latter clean and cool. 110

Minor changes may be made without departing from the spirit and scope of the in- 110 vention as claimed.

What I claim as new is:—

1. An abrading and polishing tool comprising a casing, polishing mechanism ar- 115 ranged therein, said casing being provided with an arcuate series of notches, eccentric devices interposed between said mechanism and said casing for supporting the mechanism for rotation, and a bail passing around the casing and having its extremities connected to said devices for adjusting the same and adapted to have detachable engagement with any one of said notches. 120

2. An abrading and polishing tool includ- 125 ing adjustably mounted and relatively spaced eccentric rings, supporting discs arranged in the rings, a motor arranged between the supporting discs and secured to one of them, a spider secured to the other supporting disc 130

between the same and motor, an abrading and polishing drum surrounding the motor and rotatably supported by the same and the spider, a pinion fixed to the shaft of the motor, 5 gears journaled on the spider and meshing with the pinion, and a gear fixed to the drum and meshing with said first gears.

3. An abrading and polishing tool including eccentric rings arranged in relatively 10 spaced relation and adjustably mounted, supporting discs arranged in the rings, a motor

arranged between the supporting discs and secured to one of them, a spider secured to the other supporting disc between the same and the motor, an abrading and polishing drum 15 surrounding the motor and spider and rotatably supported by said parts, and means establishing a driving connection between the motor and drum.

In testimony whereof I affix my signature.

HAROLD A. SWAN.
